UNITED STATES PATENT OFFICE.

FRANK F. ENO, OF MANCHESTER, NEW HAMPSHIRE, ASSIGNOR TO PLANT BROS. & CO.,
OF MANCHESTER, NEW HAMPSHIRE, A CORPORATION OF MAINE.

SHOE.

Application filed September 27, 1922. Serial No. 590,822.

To all whom it may concern:

Be it known that I, FRANK F. ENO, a citizen of the United States, and a resident of Manchester, county of Hillsborough, 5 State of New Hampshire, have invented an Improvement in Shoes, of which the following description, in connection with the accompanying drawings, is a specification, like characters on the drawings representing like parts.

My invention relates to shoes and particularly but not exclusively to a heel pad or other covering for the inside bottom surface of the shoe.

15 My invention, which has among its objects the provision of means for reliably securing a heel pad in place in a simple and convenient manner, will be best understood from the following description when read 20 in light of the accompanying drawings of one specific embodiment of my invention selected for illustrative purposes, while the scope of my invention will be more particularly pointed out in the appended claims.

25 In the drawings,

Fig. 1 shows an elevation of a shoe with parts broken away;

Fig. 2 is a section on the line 2—2 of Fig. 1; and

30 Fig. 3 is a perspective view showing the heel pad before insertion into the shoe.

Referring to the drawing which shows the particular embodiment of my invention selected for illustrative purposes I have shown

35 a shoe of common construction, the same including the sole 1 having the shank 3, the heel 5, and uppers 7, together with an insole 9.

It is common to provide shoes with heel

40 or sock pads covering the heel end of the inside bottom surface of the shoe and other coverings for this surface for protective and finishing purposes. The usual manner of securing such parts to the inside bottom

45 surface of the shoe is by cementing the parts thereto. As it is well known, this method of securing has proved universally unsatisfactory, the parts loosening and slipping due to softening of the cement when subjected to

50 moisture and the heat generated by the foot of the wearer. My invention aims, among other things, to eliminate this disadvantage.

To this end the covering for the inside bottom surface of the shoe, which covering is herein exemplified by one type of heel pad,

is nailed as well as cemented to the inside bottom surface of the shoe, the heel pad of course fitting the heel end of this surface and all or at least some of the nails being placed away from the rear end of the heel portion 60 and in such manner that their heads are covered by the upper portion of the pad. As herein shown I have provided two nails placed at opposite sides of the shoe near the front end of the heel and for causing the 65 heads of the nails to be covered both nails extend through a flap on the under side of the heel pad.

As shown the heel pad consists of an upper piece of sheet material 11 and a lower 70 piece 13 both preferably being of leather. Both nails pass through the same flap which flap is formed by sewing the pieces 11 and 13 together in such manner as to provide a portion 17 at the front of the lower piece 75 capable of being separated therefrom. Herein the pieces are sewed about their edges as indicated at 15 the stitches terminating near the front of the lower piece thus in the particular type of heel pad illustrated 80 causing the flap to extend transversely across the lower side of the upper piece.

The length of the pieces 11 and 13 relatively to each other and to the shoe will depend on the shape of the shoe and finish 85 desired. Herein I have shown the upper piece extending the full length of the shank of the shoe and the lower piece terminating at the top of the shank. It will be understood however that the upper piece need extend no further toward the front of the shoe than the lower piece; also that by terminating the lower piece over the top of the shank the nails may be placed so as not to be under the ball of the heel of the wearer. 90

In practice the pieces 11 and 13 of the heel pad or other covering are first cut to shape and sewn together, to give a structure such as described, whereupon cement is supplied to the under surface of the pad, and the parts are placed in position in the shoe and the pad thus cemented in place. The member 11 is then bent back so as to expose the flap 17 which is then secured to the shoe, preferably by nailing it thereto, as indicated 100 by the nails 19. After this the piece 11 is bent back into place, and if desired may be likewise cemented in place.

I have found that the softening of the cement due to the wearing of the shoe, al- 110

though sufficient to permit sliding of the heel pad, is yet sufficient to cause it to remain in contact with the inside bottom surface of the shoe if the nails 19 are provided to prevent the sliding. I have found that the best results are secured by placing the nails at opposite sides of the pad, for this, with the flap for example positioned as shown, prevents not only longitudinal and transverse sliding of the pad but rotary sliding as well.

Although I have described for purposes of illustration one specific embodiment of my invention it will be understood that I am not limited thereby to its particular mechanical details, but that within the scope of my invention wide deviations may be made therefrom without departing from the spirit of my invention.

20. Claims:

1. In a shoe, the heel pad or the like comprising a piece of sheet material conforming to the inside portion of the bottom of the shoe adjacent the heel thereof and a second piece of sheet material beneath the first, the two pieces being sewed together at their edges except adjacent the front end of the second piece whereby to provide a flap beneath the first piece, said flap being nailed to said shoe, and the under side of said pad being cemented to said shoe.

2. In a shoe, the combination with a sheet of covering material for the rearward end portion of the inside bottom surface of the shoe, of a separate piece of sheet material sewed at its edges except at its forward end portion to the first mentioned sheet to provide beneath the latter a narrow transverse flap, said flap near its ends being secured to the adjacent portion of the inside bottom surface of the shoe by nails or the like.

3. In a shoe, a heel pad or the like fitting the heel portion and shank portion of the bottom of said shoe, said heel pad having a piece of sheet material on its under side extending slightly over the shank portion, the two pieces being sewed together at their edges, and the unsewed portion of said piece being nailed to said shank portion.

4. In a shoe, the combination with a sheet of covering material for the inside bottom surface of the shoe, of means for securing said sheet of covering material to said bottom surface, said means comprising a piece of sheet material sewed at its edges except at its forward end portion to the under side of said sheet of covering material to provide beneath the latter a narrow transverse flap, said flap being nailed to said inside

bottom surface of the shoe, and the nails being covered by said sheet of covering material.

5. In a shoe, a heel pad or the like comprising two superimposed pieces of sheet material fitting the heel end of the inside bottom surface of the shoe, both pieces of sheet material being of lesser length than said inside bottom surface of the shoe and the upper piece being longer than the lower piece, means for permanently securing said pieces to each other in such manner as to cause the front end of the lower piece to form a transverse flap beneath the upper piece, and means for securing said flap to said inside bottom surface of said shoe.

6. In a shoe, a heel pad or the like comprising two superimposed pieces of sheet material fitting the heel end of the inside bottom surface of the shoe, both pieces of sheet material being of lesser length than said inside bottom surface of the shoe, means for permanently securing said pieces to each other in such manner as to cause the front end of the lower piece to form a transverse flap beneath the upper piece, and nails positioned at opposite ends of said flap for securing said flap to said inside bottom surface of said shoe.

7. In a shoe, a heel pad or the like comprising two superimposed pieces of sheet material covering the heel end of the inside bottom surface of the shoe and of such length as to extend to the shank of said shoe, said pieces of sheet material being sewed to each other in such manner that the front end of the lower piece forms a transverse flap beneath the upper piece lying across the upper part of the shank of said shoe, and said flap being secured to said shank by nails or the like positioned at opposite ends of said flap.

8. In a shoe, a heel pad or the like for the inside bottom surface of said shoe, a narrow strip of material constituting a flexible flap on the under side of said pad extending transversely across said surface, said flap being positioned at a point near the front of the heel portion of said surface, and being separated from the body of said pad at the forward transverse edge of said flap to permit separation of said body and flap by relative bending about the rearward transverse portion of said flap, and fastening means for rigidly securing said flap to said surface at widely separated points.

In testimony whereof, I have signed my name to this specification.

FRANK F. ENO.
